UNITED STATES PATENT OFFICE

HERBERT E. TUCKER, OF SOUTH BEND, INDIANA, ASSIGNOR TO UNIVERSAL DRAFT
GEAR ATTACHMENT CO., A CORPORATION OF ILLINOIS

DRAFT GEAR

Application filed July 9, 1927. Serial No. 204,618.

This invention relates to shock absorbers, and more particularly to draft gears for railway cars.

One of the objects of the invention is the provision of a draft gear having new and improved means for automatically compensating for the wear on the friction elements.

Another object of the invention is the provision of a new and improved draft gear having new and improved means for releasing the gear after compression.

A further object of the invention is the provision of a new and improved arrangement of parts of a draft gear whereby the capacity of the gear may be materially increased without increasing its overall dimensions beyond the normal gear.

A still further object of the invention is the provision of a gear that is cheap to manufacture, simple in construction, efficient in operation, composed of few parts, and that is not likely to become broken, distorted or get out of order.

Other and further objects and advantages 25 of the invention will appear from the following description taken in connection with the accompanying drawings, in which—

Fig. 1 is a longitudinal vertical section of the gear showing the same in position in the 30 yoke;

Fig. 2 is a section on broken line 2—2 of Fig. 1;

Fig. 3 is a perspective view of one of the pressure creating wedge members;

Fig. 4 is a perspective view of one of the wear compensating members;

Fig. 5 is a longitudinal vertical section of a different type of gear showing a modified form of the invention in position therein;

Fig. 5^a shows in longitudinal section various of the elements of the gear shown in Fig. 5.

Fig. 6 is a section on line 6—6 of half of the gear;

Fig. 7 is a perspective view of one of the wear compensating members;

Fig. 8 is a perspective view of one of the wedge members;

Fig. 9 is a longitudinal vertical section of

a modified form of construction from that shown in Fig. 5;

Fig. 10 is a transverse section of half of the gear on the line 10—10 of Fig. 9;

Fig. 11 is a section on line 11—11 of Fig. 9, with parts broken away;

Fig. 12 is a longitudinal section of one end of a gear showing a modified form of the device in position therein; and

Fig. 13 is an exploded view of the wedging and compensating members at one side of the gear.

In draft gears of the frictional type the parts become worn by constant use and unless provision be made for compensating for this wear the gear will soon become worn and the relative position of the parts so changed that the efficiency of the gear will become greatly impaired. The present invention contemplates the use of novel means for automatically taking up the wear incident to the use of the gear whereby the parts will be maintained in friction-creating position throughout the entire life of the gear.

In the form of construction illustrated in Figs. 1 and 2, the characters 10, 11 designate pusher elements seated against the usual followers 14, 15. These pushers are four in number, two being located at each end and at opposite sides of the gear and preferably being united by webs 12, 13. The conventional coupler yoke 16 extends about the gear in the usual manner.

A group of two sets of intercalated friction plates, 17 and 18, are mounted between the followers. The set of friction plates 17 are associated with the follower casing 12 and the set 18 with the casing 13.

The marginal walls of the casings may, if desired, be rabbeted at their outer ends, as shown at 19 in Fig. 2, in which the abutment or contact plates 21 are adapted to be placed. The marginal edge of the rabbet at each end of the plate is peened over onto the plate as shown at 21 in Fig. 2 for holding it firmly in position. The plate 21 may be omitted if desired, it being used to close the casing formed by the pushers and their connecting webs after the plates have been inserted, and to provide a smoother abutting surface for

the friction plates. Furthermore, these plates are of softer metal than the followers, and hence are not so likely to distort the ends of the friction plates should they become 5 slightly tilted in compressing the gear.

The wedging mechanism for compressing the friction plates and for automatically compensating for the wear on the plates will now be described.

10 Since the casings 12 and 13 and the associated wedging mechanisms are substantially alike, only one need be described. Each casing is provided with oppositely arranged inwardly extending ledges or supports 22 against each of which a flat face 23 of a friction creating wedging member 24 engages. The wedge member is provided with an inclined face 25 for engaging a corresponding face of the friction shoe or shoe member 26, 15 for forcing the latter laterally into frictional engagement with the friction plates. The wedge 24 is also provided with an inclined face 27 for engaging a corresponding inclined face on a wear compensating wedge member 28.

20 The outer side face of the wedge member 28 reacts against the inner wall 31 of the casing, and in order to strengthen the casing at this point the same may be provided with a 25 reinforcing rib 29, see Fig. 2.

30 Suitable means are provided for resisting the longitudinal movement of the shoes 26 at each end of the gear. As shown, a spring seat 32 at each end of the gear is employed for this purpose. A spring 33 is interposed between these seats. Each of the seats is provided with oppositely arranged inclined faces 34 for engaging a corresponding inclined face of the projection or shoulder 35 on each shoe member 26. The cooperating faces 34 and 35 facilitate the lateral movement of the shoe 35 during compression of the gear.

40 The spring seat 32 also engages a flat face of each of the wear compensating wedge members 28 as clearly shown in Fig. 1 of the drawings, whereby when the gear is compressed both wedge members 24 at each end of the gear will be forced laterally against the shoe 26, which in turn will be forced 45 against the friction plates. Each of the spring seats 32 extends about the plates and is provided at opposite sides with the spaced longitudinally extending flanges 30 and 40 for engaging the inner and outer sides of the 50 forward end of the casing at opposite sides of the gear for positioning said seat, as clearly shown in Fig. 2.

55 One or more of the friction plates of each set are preferably though not necessarily 55 slightly tapered as shown at 36 and 37 for increasing the lateral pressure on the plates when the gear is compressed and for facilitating its release when the pressure is removed.

60 The expansion of the gear is limited in any

suitable manner as by means of the rods 39, which extend through suitable flanges 41 on the followers, as shown at the right in Fig. 2.

Suitable means are provided for retracting the friction plate. In the form of the device 70 shown in Figs. 1 and 2 the webs are provided with inwardly extending shoulders 42 and 43 which are adapted to engage shoulders 44 formed by the enlarged end 45 of said plates. The shoulders 44 of the plates are also engaged 75 by the inner flanges 40 of the spring seat 32. Either of these retracting means may be employed without the other when necessary or desirable. The plates are spaced slightly from the followers to permit an initial wedging action of the wedging mechanism, as is usual in such constructions.

The shoe engaging plates are preferably, though not necessarily shorter than the other plates in order to equalize the wear on the 80 shoes at opposite ends of the gear.

The inclined face 25 of the wedge member 24 may be and preferably is much more acute than the inclined face 27 of this member. That is, it forms a more acute angle with the longitudinal axis of the gear than does the face 27. As a result of this construction, the shoes are forced laterally against the friction plates with tremendous force when the gear is compressed. By making the inclined face 27 only slightly greater than the "pressure angle" or "angle of repose", a ready release of the gear is insured with the use of the single spring 33. Furthermore, the wear on the friction plates is readily taken up by the wedging action of the wear compensating wedge member 28 reacting against the face 27, without materially decreasing the space between the ends of the friction plates and the follower. The angle of the face 27 is so "flat" that a slight rearward movement, or movement toward the follower, of the wedge member 28, will cause a considerable inward or lateral movement of the wedge member 24. This is considered an important 100 feature of the invention because the wear on the plates may be compensated for by a slight rearward or outward movement of the wedge member 28, spring seat 32 and associated friction plates. Another important 105 feature of this arrangement of the wedging faces is that on release the action of the spring on the wedge member 28 will tend to force the casing rearward, thereby relieving the wedging action between the wedge member 24 and the shoe 26 with but a slight wedging action between the wedge members 24 and 28 due to the slight inclination of the face 27.

110 In the operation of the device upon the compression of the gear, the followers 14 and 15 will approach each other, causing the wedge members 24 to be forced inwardly between the friction shoes 26 and the wear compensating members 28.

115 The wear compensating members are pre- 120

vented from moving laterally outward by the walls of the casings 12 and 13, and their longitudinal movement is resiliently resisted by the spring 33 through the spring seats 32, 5 consequently the shoes are forced against the plates with tremendous pressure, depending on the sharpness of the angle of the wedging face 25. Both inclined faces 27 and 25 co-operate to force the shoes against the friction plates. The friction between the inclined faces of the wedges and friction shoes; 10 between the wedging and wear compensating members; between the shoes and the spring seats; between the wear compensating members and the walls of the casings; and the friction between the wedging members 15 and the supports or ledges on the casing absorbs a certain amount of the energy in compressing the gear, and the friction of the plates and the resistance of the spring absorb the remainder under normal buffs and 20 pulling strains. The lateral reaction of the compressive force applied to the plates is transmitted through the element 28 in part 25 to the casing 13 and in part to the spring, the element 24 being advanced by the wedging action of the element 28.

By means of this arrangement the angle of the wedging face 25 may be so acute that 30 with the conventional type of gear it would stick and not release, but with the use of the wear compensating members 28 engaging the face 27 of a broader angle the spring will move the follower rearward with but a slight 35 wedging action, thus releasing the lateral pressure of the wedge 24 on the shoe 26 even though the angle be very acute. This arrangement permits the use of a very acute incline between the wedging faces of the shoe 40 member and wedge 24 whereby the capacity of the gear is greatly increased without interfering with its prompt release. In other words, in compressing the gear the wedging action of the wedge members 24 against the 45 friction shoes is direct, while on release, the wedging action is indirectly through the compensating members 28. But the "flatness" of the angle between the wedging and wear compensating members results in forcing the 50 wedging members outwardly longitudinally of the gear instead of laterally inwardly, thereby releasing the wedging action and permitting the spring to return the parts to normal position. This is considered an important 55 feature of applicant's invention because a maximum wedging action on the friction plates is produced when the gear is compressed, and a minimum wedging action is created on said plates when the gear is released, thus providing a high capacity gear 60 with a prompt release.

In Figs. 5 to 8 are shown a construction in which the compensating mechanism is modified to adapt it to be used on the end plate 65 type of gear, that is, a gear in which the inter-

calated friction plates are at one end of the gear and the resilient means at the other.

Since this is a well known type of gear a brief description of the parts is thought to be sufficient. The gear comprises a chambered follower 46 and a plate follower 47. A group of two sets of intercalated friction plates 48 and 49, respectively, are mounted in the chambered follower at each side of the longitudinal axis of the gear. The plates 48 are interlocked with the follower 46 in the usual manner by the ribs or projections 51 engaging in corresponding grooves 52 in the chambered follower. The yoke is shown at 53 and the coupler butt at 54.

One or more of the plates 48, as the plates 55, are tapered slightly to facilitate release, in a manner well known in the art.

Suitable means are provided for creating lateral pressure on the plates when the gear is compressed. As shown, a friction shoe 56 is provided for engaging each group of plates. Each shoe is provided with one or more inclined or wedging faces. Preferably two of these wedging faces 57 and 58 are employed, in order that the lateral pressure shall be equalized on each end of the plates. Wedge members 59 and 61 having inclined faces 50 and 60 are provided for engaging the inclined faces 57 and 58 of the shoes between the flanges 40', see Fig. 6. The flanges 40' assist in positioning the wedges. The wedge members 59 and 61 are provided with bases 62 extending transversely to the gear which are seated on forwardly facing shoulders 63, 64 on a central thrust member 65 which in turn is in constant engagement with the follower 47.

Wear compensating members 66, 67 are interposed between each side of the thrust member 65 and each of the wedge elements 59 and 61, the engaging faces of the elements 66, 67 and 59, 61 in each instance, being formed as forwardly and outwardly directed wedge surfaces 71, 72 and 60, 60. Preferably the elements 66, 67 at each side of the thrust member are united at their ends, thus forming rectangular bodies 69 which enclose the bosses 68 upon which the shoulders 62, 64 are formed and maintain the parts in proper relation.

Means are provided for resisting the inward movement of the shoes 56 and for returning the parts to inoperative position after compression. In the form of the device selected to illustrate one embodiment of the invention, suitable springs are employed for this purpose.

As shown in Fig. 5 spring seats 73 and 74 are provided which extend across the inner ends of the friction plates 49 at each side of the longitudinal axis of the gear such seats being integrally united to insure smoothness of action.

Springs 75 and 76 are interposed between these seats and the end 77 of the chambered

130

follower 46. These springs resist the inward movement of the shoes 56 and are adapted to return the same to normal position after compression. In order to lighten the spring seats 73 and 74 they may, if desired, be provided with ribs 78 for engaging the ends of the friction plates.

Spring means are also provided for resisting the inward movement of the central member 65 and for releasing the wedging action after compression of the gear. As shown, the central member 65 is provided with a spring seat 79 which is adapted to engage the inner end of said central thrust member. A release spring 81 is interposed between the seat 79 and the end 77 of the casing.

When the parts have been assembled, a key 82 inserted through transverse openings in the chambered follower and the central thrust member 65 holds the latter in position. The key is held in position by a projection 85 on the spring seat 79 which extends axially through the end portion of the pusher member 65 and seats in a recess 86 in said key.

As in the former construction, the wedge members 59 and 61 have the friction shoe engaging faces 50 arranged at a sharp angle while the inclined faces 60 which engage the wear compensating members 69 are arranged at a much less acute angle whereby on release the pressure of the wear compensating member on the inclined face will have but a slight wedging action against the plates, and any wear of the plates will be compensated for with a minimum rearward movement of said wear compensating member.

In the operation of the gear, when the same is compressed the thrust member 65 is advanced, carrying with it the wedge members 59 and 61 which have their wedging faces forced between the friction shoes 56 and the wear compensating members 69. The spring 81 resists the inward movement of the wear compensating members 69 whereby lateral pressure is applied to the friction plates. On further compression of the gear the follower 47 will come into contact with the ends of the friction plates 49 and move the same inward for absorbing the shock by the friction of the interengaging parts.

On release of the gear, the release spring 81 will force the wear compensating member 69 rearwardly, which, acting on the inclined faces 60 of the shoes will move the same rearwardly to release the lateral pressure on the shoes and permit the springs 75 and 76 to move the shoes and plates rearwardly to normal inoperative position. It will be noted that the outer ends of the plates 49 are spaced slightly from the follower plate 47, whereby upon the initial compression of the gear the wedging mechanism is set up before the friction plates begin to move.

The form of the device shown in Figs. 9, 10 and 11 differs but little from that shown

in Figs. 5 to 8, inclusive. In this form of the device the wedging mechanism is not operated on by the release spring 87 which operates only on the central thrust member 88. The springs 89 and 91 alone resist the inward movement of the wedging mechanism. The friction plates are substantially the same as in Figs. 5 to 8 and are designated by the same reference characters. They need not be further described. The central thrust member is provided with a reduced portion 92 forming the shoulders 93 against which the wedge members 94 are adapted to engage. The wedging faces 95 and 96 of the wedge members 94 engage corresponding inclined faces on the friction shoes 97 and the wear compensating members 98, respectively.

The inner ends of the shoes 97 and compensating members 98 are provided with opposed inclined faces that are adapted to be engaged by wedge blocks 99 similar to the blocks 94, the bases of which are engaged by the spring seats 101 and which, as in the other form, are integrally united. In the construction shown in Figs. 5 to 8 the wedge members 59 are all turned in the same direction, whereas in the construction shown in Figs. 9 to 11 the corresponding wedge members 94, 99, have their apexes turned toward each other, as clearly shown in Fig. 9.

In the operation of this device the compression of the gear will force the wedge members 94 between the shoes 97 and wear compensating members, and will force said shoes and compensating members forwardly. The forward movement of these parts will be resisted by the springs 89 and 91 which, acting on the wedge members 99, will tend to drive the wedge members between the shoes and wear compensating members, thereby creating considerable lateral pressure on the friction plates 48 and 49. The wedging faces 95 and 96 of the wedging members 94 and 99 correspond to the inclined faces 25 and 27 respectively of the wedging members 24 of the form of the device shown in Figs. 1 to 4, and function in a similar manner.

The form of the device shown in Figs. 12 and 13 is a modification of the construction shown in Figs. 9, 10 and 11. Since the type of gear is the same, and the arrangement of the plates, springs, thrust members, and followers is the same, it is not thought necessary to repeat the description of these members in detail or to show the entire gear on the drawing.

In this form of the device, the friction shoes and inner wedge members are made integral instead of being separate elements as in the construction shown in Fig. 9.

In this construction, the friction shoes 125 which engage the friction plates 126 at each side of the gear are provided with the inclined faces 127 and 128 respectively. The

inclined face 127 engages a corresponding inclined or wedging face 129 on the inner end of the wear compensating member 131. The outer end of each of the wear compensating members 131 is provided with an inclined or wedging face 132 for engaging a corresponding inclined face 133 on the wedge member 134. The wedge member 134 is provided with a wedging face of a "sharp" angle 135 for engaging the inclined face 128 of the friction shoe. As in the previously described construction, the face 133 of the wedge member is what, for convenience, may be termed a "flat" angle, as distinguished from the "sharp" angle of the face 135. As in the construction described above the wedge members 134 each has one side engaging a shoulder 136 formed by the reduced portion 137 on the thrust member 138.

20 The pin or key 139 for holding the parts in assembled relation is held in position by a spring pressed detent, as the ball 141, which is adapted to engage a recess 142 in the pin or key 139.

25 In the operation of this form of the device upon compression of the gear, the thrust member will force the wedge members 134 inwardly between the shoes 125 and wear compensating members 131 against the compression of the springs 142. The springs 142 will resist the inward movement of the members 131, whereby the shoes which are not resisted directly from moving inward by the springs will move inward relative to those members, thereby wedging said shoes at both ends against the plates 126 and forcing the members 131 against the reduced portion 137 of the thrust member 138.

Upon releasing the gear the wedge member 134 will automatically loosen up due to the flatness of the surface 133, and this will permit the loosening up of the wedging surfaces 127 and 129 for the same reason and the springs will return the parts to normal expanded position.

50 It will be observed that in all these devices the inclined faces between the wedging members and the wear compensating members are arranged at an angle slightly greater than the angle of repose, and that the inclined faces between the wedging members and the friction shoes or friction members are arranged at a sharp or an acute angle, whereby a maximum wedging action will be produced when the gear is compressed, and a minimum wedging action will be produced during the release of the gear.

I claim as my invention:

60 1. In a draft gear, a pair of opposed followers, two sets of intercalated friction plates between said followers, one set movable with one follower and the other set with the other follower, friction shoes for engaging said plates, wedge members frictionally engaging said followers and shoes, wear compensating

members frictionally engaging said followers and wedge members and means for yieldingly resisting the inward movement of said shoes and compensating members on the compression of said gear.

70 2. In a draft gear, in combination, opposed followers, cooperating friction elements located between the followers and relatively movable thereby, wedging friction shoes cooperating with such elements, a thrust member, wedges movable with the thrust member and cooperating with the shoes, wear compensating elements having sliding bearing against a longitudinal wall of the thrust member and inclined faces for urging the wedge elements together, and spring means for resisting the advance of the wear compensating elements and the compression of the gear.

75 3. In a draft gear in combination, a pair of opposed followers, a group of intercalated friction plates between the followers, the plates of each set being engagable by one of the followers, a pair of friction shoes engaging each end portion of the group of plates, 80 each shoe having a forwardly and outwardly inclined wedging face and an inwardly facing shoulder forward of such face, a pair of pusher elements cooperating with each follower, one at each side of the gear, a wedge element slidably seated on each pusher and having an inclined face cooperating with the wedge face of one of the shoes, a spring seat surrounding the group of plates and engaging the shoe shoulders, a helical spring enclosing the group of plates and reacting between the seats and means for urging the wedge elements laterally toward the shoes.

85 4. In a draft gear in combination, a pair of opposed followers, a group of intercalated friction plates between the followers, the plates of each set being engageable by one of the followers, a pair of friction shoes engaging each end portion of the group of plates, 90 each shoe having a forwardly and outwardly inclined wedging face and an inwardly facing shoulder forward of such face, a pair of pusher elements cooperating with each follower, one at each side of the gear, 95 a wedge element seated on each pusher and having an inclined face cooperating with the wedge face of one of the shoes, a spring seat surrounding the group of plates and engaging the shoe shoulders, a helical spring enclosing the group of plates and reacting between the seats and means for urging the wedge elements laterally toward the shoes.

100 5. In a draft gear in combination, a pair of opposed followers, a group of intercalated friction plates between the followers, the plates of each set being engageable by one of the followers, a pair of friction shoes engaging each end portion of the group of plates, 105 each shoe having a forwardly and outwardly inclined wedging face and an inwardly facing shoulder forward of such face, a pair of pusher elements cooperating with each follower, one at each side of the gear, 110 each pusher element having a forwardly projecting outer wall, a wedge element seated on each pusher and having an inclined face cooperating with the wedge face of one of the shoes and an outer face forwardly and inwardly inclined at a more obtuse angle than its first named face, a spring seat surrounding the group of plates and engaging the shoe shoulders, a helical spring enclosing the group of plates and reacting between the seats, and a wear compensating block interposed between each wedge element and a spring seat and having a bearing on the named wall of the pusher.

115 6. In a draft gear in combination, a pair of opposed followers, a group of intercalated friction plates between the followers, the plates of each set being engageable by one of the followers, a pair of friction shoes engaging each end portion of the group of plates, 120 each shoe having a forwardly and outwardly inclined wedging face and an inwardly facing shoulder forward of such face, a pair of pusher elements cooperating with each follower, one at each side of the gear, each pusher element having a forwardly projecting outer wall, a wedge element seated on each pusher and having an inclined face cooperating with the wedge face of one of the shoes and an outer face forwardly and inwardly inclined at a more obtuse angle than its first named face, a spring seat surrounding the group of plates and engaging the shoe shoulders, a helical spring enclosing the group of plates and reacting between the seats, and a wear compensating block interposed between each wedge element and a spring seat and having a bearing on the named wall of the pusher.

125 7. In a draft gear in combination, a pair of opposed followers, a group of intercalated friction plates between the followers, the plates of each set being engageable by one of the followers, a pair of friction shoes engaging each end portion of the group of plates, 130 each shoe having a forwardly and outwardly inclined wedging face and an inwardly facing shoulder forward of such face, a pair of pusher elements cooperating with each follower, one at each side of the gear, each pusher element having a forwardly projecting outer wall, a wedge element seated on each pusher and having an inclined face cooperating with the wedge face of one of the shoes and an outer face forwardly and inwardly inclined at a more obtuse angle than its first named face, a spring seat surrounding the group of plates and engaging the shoe shoulders, a helical spring enclosing the group of plates and reacting between the seats, and a wear compensating block interposed between each wedge element and a spring seat and having a bearing on the named wall of the pusher.

friction plates between the followers, the plates of each set being engageable by one of the followers, a pair of friction shoes engaging each end portion of the group of plates, each shoe having a forwardly and outwardly inclined wedging face and an inwardly facing shoulder forward of such face, a pair of pusher elements engaging each follower, one at each side of the gear and having a forwardly projecting outer wall, a wedge element seated on each pusher and having an inclined face cooperating with the wedge face of one of the shoes, an outer face forwardly and inwardly inclined at a more obtuse angle than its first named face, a spring seat surrounding the group of plates and engaging the shoe shoulders, the shoulders and engaging portions of the seats being backwardly and outwardly inclined, a helical spring enclosing the group of plates and reacting between the seats, and a wear compensating block interposed between each wedge element and the spring seat and having a bearing on the named wall of the pusher.

25 In testimony whereof I affix my signature.
HERBERT E. TUCKER.
